UNITED STATES PATENT OFFICE.

WILLIAM C. KELLY, OF CHARLESTON, WEST VIRGINIA, ASSIGNOR TO THE KELLY AXE MANUFACTURING COMPANY, OF CHARLESTON, WEST VIRGINIA, A CORPORATION OF WEST VIRGINIA.

SCYTHE.

1,279,354.

Specification of Letters Patent. Patented Sept. 17, 1918.

Application filed December 16, 1916. Serial No. 137,339.

To all whom it may concern:

Be it known that I, WILLIAM C. KELLY, residing at Charleston, in the county of Kanawha and State of West Virginia, a citizen of the United States, have invented or discovered certain new and useful Improvements in Scythes, of which improvements the following is a specification.

My invention relates to improvements in the construction of scythes; the object in view is simplicity combined with serviceability.

The invention is illustrated in the accompanying drawings. Figure 1 shows in side elevation the scythe of my invention; Fig. 2 is a view in side elevation of the heel end of the same scythe, seen from the opposite side; Figs. 3, 4, and 5 are sectional views, the planes of section being indicated in Fig. 2 by the lines III—III, IV—IV, and V—V, respectively.

The scythe consists essentially of the blade 1 and the tang 2. The blade is, as will readily be perceived on comparing Figs. 1, 2, 25 and 4 of the drawings, provided, on its upper side and along its rear edge and extending from its heel toward its tip with a groove; and, since the blade will ordinarily be formed of sheet metal, this groove may 30 be provided by shaping the blade with a marginal sinuosity 3.

The tang 2 is, in that part which engages the blade, bifurcated, being formed into two arms, 4 and 5 (preferably of unequal 35 length) with a cleft between them. One of the arms (the longer one, in my preferred construction) is provided along its inner face, and preferably throughout that portion by which it exceeds the other arm in length, 40 with a rib 6 (Fig. 4).

When the parts are assembled the heel of the blade 1 rests in the cleft between the

arms 4 and 5 of the bifurcated tang (cf. Figs. 1, 2, and 4); the two arms 4 and 5 of the tang overlie opposite faces of the blade; the rib with which the longer arm 4 is provided rests in the groove formed as has been said marginally in blade 1. The blade and tang being so assembled, they may be united, as by rivets 7, extending through both arms 45 of the bifurcated tang and through the blade resting in the cleft between them, and blade and tang may be additionally secured by rivets 8 extending through blade 1 and the longer arm 4 of the tang. 50

It will be observed (cf. Figs. 1 and 5) that the heel end of the blade may be made to abut squarely against a correspondingly disposed wall at the bottom of the cleft in the tang; and that the outer margin of the arm 60 4 of the tang may engage squarely a vertically disposed flange forming the outer bend of the sinuosity 3 (cf. Figs. 2 and 6). Such a particular shaping and arranging of parts makes for rigidity and durability. 65

I claim as my invention:

In a scythe the combination of a grooved blade and a bifurcated integral tang, one of the arms of the bifurcated tang being longer than the other and being provided on its inner face with a rib, the heel of the blade resting between the arms of the bifurcated tang, the rib on the longer arm of the tang resting in the groove in the blade, and rivets 70 extending through both arms of the bifurcated tang and through the blade resting between them. 75

In testimony whereof I have hereunto set my hand.

WILLIAM C. KELLY.
